United States Patent Office

Des. 219,554
Patented Dec. 22, 1970

219,554

FOLDING VIEWER FOR NARROW FILM

Adolf Prazsky, Prague, Czechoslovakia, assignor to
Meopta, Prerov, Czechoslovakia, a national enterprise

Filed Feb. 4, 1970, Ser. No. 21,269

Claims priority, application Czechoslovakia Aug. 5, 1969

Term of patent 7 years

Int. Cl. D16—04

U.S. Cl. D61—1

*FIG. 4.**FIG. 5.*FIG. 1 is a perspective view of the folding viewer, with the parts in folded or closed relation and showing my new design;

FIG. 2 is a top plan view thereof;

FIG. 3 is a side elevation thereof;

FIG. 4 is a front elevation thereof; and

FIG. 5 is a perspective view of the viewer in open position.

I claim:

The ornamental design for a folding viewer for narrow film, substantially as shown and described.
